UNITED STATES PATENT OFFICE.

LUCIUS B. TUTTLE, OF NEW HAVEN, CONNECTICUT.

DESIGN FOR CLOCK-FRAMES.

SPECIFICATION forming part of Design No. 11,676, dated March 9, 1880.

Application filed February 6, 1880. Term of patent 7 years.

To all whom it may concern:

Be it known that I, LUCIUS B. TUTTLE, of the town and county of New Haven, and State of Connecticut, have originated and designed 5 a Pattern for Clock-Frames, of which the following is a full, clear, and exact description, reference being had to the accompanying drawing, making part of this specification.

A represents the body of the frame. Each 10 upper corner of the frame is ornamented by a triangular cut or opening, *a*, and between these is a diamond-shaped space, *b*. In the middle portion is a large space, *B*, symmetrical in form and extending from side to side of the frame. 15 At the lower middle portion is a triangular space, *c*, surrounded by arms *d*, that form a triangle.

Heretofore clock-frames have been made for utility, without much regard to symmetry and ornamentation. My design is intended to combine symmetry and utility, forming a frame that is novel and ornamental in appearance. 20

What I claim as my invention is—

A design for a clock-frame symmetrical in outline and ornamented with triangular and 25 diamond-shaped spaces, in the manner above described.

LUCIUS B. TUTTLE.
